UNITED STATES PATENT OFFICE.

CHARLES F. PETERSON, OF NEW YORK, N. Y.

FUEL-BURNER.

1,196,808.

Specification of Letters Patent.

Patented Sept. 5, 1916.

Application filed March 3, 1913. Serial No. 751,743.

To all whom it may concern:

Be it known that I, CHARLES F. PETERSON, a citizen of the United States, residing at New York, in the county of New York and State of New York, have invented certain new and useful Improvements in Fuel-Burners, of which the following is a specification.

This invention relates to improvements in liquid fuel burners and has for its object to provide a simple, efficient, and inexpensive burner adapted to provide a heater whereby heat may be diffused very effectively and evenly from a comparatively small combustion chamber.

A further object of my invention consists in providing, in a device of the kind described, improved means for stimulating the inflow of air to the combustion chamber, and also to provide suitable passages for conveying air heated during its transit through the heater.

With the above and other objects in view my invention consists in the combination, arrangement, and details of construction disclosed in the drawings and specification and then more particular pointed out in the appended claims.

In the drawings, wherein similar reference characters designate similar parts throughout the respective views, Figure 1 is a vertical elevation of my heater, partly in section and broken away, showing the combustion chamber from the side, Fig. 2 is a cross-sectional elevation of my invention with the surrounding open-ended hood removed, Fig. 3 is a top plan view of my heater with the hood removed, Fig. 4 is a fragmental detail view of one end of my wick-containing chamber, Fig. 5 is a detail sectional view of a wick-controlling device, Fig. 6 is a transverse, fragmental sectional view of Fig. 4, Fig. 7 is a longitudinal sectional view of Fig. 5, Fig. 8 is a bottom plan view of my heater, and Fig. 9 is an end elevation of my heater.

Referring to the drawings which are merely illustrative of my invention, an oil reservoir is designated 1 which is provided with a handle 2. A plurality of substantially rectangular draft air tubes or conduits 3 are disposed within reservoir 1 and extend above the top of said reservoir. Two of these draft tubes are shown, although if desired, the number may be increased. Four wick-containing members 5, extend longitudinally in said reservoir projecting partly above and partly below the same. Two of these members 5, it will be noticed, are on opposite sides of each of the tubes 3, and are connected at each end and at their sides by the substantially channel-shaped member 20, as is shown in Fig. 4. Each member 5 is hollow throughout and is formed at its upper end with a reduced wick-guiding part 6.

Arranged in member 5 in slidable relation is a wick-carrier 7 formed terminally with rightangular flanges 8, the upper portions 9 of which are reduced, and having racks 10 formed thereon. A rod 11 passes through the member 5, one of its extremities serving as a lug 12, which together with the opposite projecting portion carrying the handle disk 13 is arranged to take into one of the slots 14 formed in the members 20 at 75 their opposite ends, serving thereby to hold the wick containing member 5 in position in member 20. Pinions 15 are formed upon rod 11, at suitable points, arranged to mesh with the racks 10, whereby carrier 7 may 80 be raised and lowered. The wick carrier 7 is formed longitudinally, at spaced-apart points, with spring arms 16, portions of which lie flatly secured upon said carrier, while portions 17 curve outwardly and upwardly terminating in angular serrated portions 18 arranged to project into the wick 19 so as to hold the same supported relatively to the carrier, said wick 19 extending longitudinally of the member 5. It will be 90 noticed that the air draft tubes 3 extend into the oil reservoir, as shown in Fig. 2. The usual closure cap 23 is screw-threaded into the oil reservoir.

A four-sided casing 24 having supporting legs 25 is arranged to rest upon the oil reservoir and it extends around the partitions and said wick container so as to form a combustion chamber. Extending all around the top edge of casing 24 is an outwardly-extending rim 26 and said rim, at opposite sides is formed, laterally of said member 24 with a series of longitudinally-extending ports 27. Formed longitudinally of casing 24 are the spaced-apart strips 27', which are V-shaped in cross-section and having a series of ports 28 formed along the vertex line of each strip, each strip being disposed in alinement with the air conduits 3.

The member 24 is formed, substantially at 110 each side of a median line with oppositely-arranged longitudinally-extending partition

walls 29 which are arranged to project into the space 29' between the two innermost wick-containing members 5, and intermediate of the walls 29 is a similarly disposed 5 plate 30 which extends some distance below said walls. A deflector member 31 extends centrally and longitudinally of casing 24 at its top and is arranged directly over the walls 29 and plate 30, said member 31 being formed with marginal flaring portions 32 to conduct and deflect air over the wick-containing members 5. The rim 26 of casing 24 is formed at its longitudinally-opposite sides with the downwardly inclined 10 portions 33 which are bodily disposed over the outer members 5. The openings 34 are formed upon the opposite end walls 35 and 36 of member 24, and when the latter is mounted in position upon the oil reservoir, 15 said openings 34 will communicate with the interspace between the walls 29. It will also be noticed that the walls 29 are formed with upwardly and outwardly inclined portions 37. To prevent the displacement of 20 the member 24 from the oil reservoir any suitable arrangement may be used, that shown embracing the rolled members 38 which are secured upon the members 20, holes being formed upon the corners of said 25 members 24 as at 39, which register with the rolled members 38 so that the removable rods 40 may pass through said holes and said rolled members and hold casing 24 against vertical displacement. It will be 30 understood that wick 19 will project into the oil in the oil reservoir 1.

If desired the tubular member 41 may be caused to rest immediately above the casing 24, so that the device may be used for 40 cooking purposes. The rods 40 are formed with the rightangular handles 42. This member 41 will be supported upon the standard 45.

When the wicks are lighted, and properly 45 regulated, combustion will be stimulated by currents of air. These currents of air will be drawn in through the channel 29' formed between the inner wick-containing members 5, or through the air conduits 3, which currents of air will be directed by the inclined 50 portions 37 upon member 31 whose inclined portions 32 will deflect the air downwardly so as to mix with the products of combustion emanating from the wick-containing 55 members 5. The walls 29, plate 30, and the sides of casing 24 form relatively-large heat-radiating surfaces, the air being heated while passing upwardly between the walls 29, as said walls will radiate heat. The heated 60 products of combustion will impinge upon the downwardly-extending portions 37 whereby they will be deflected against the sides of the casing 24, raising the temperature of the same. Unheated air may flow to 65 the wick-containing members through the

top open end of casing 24, down member 41. Circulation of air is very nicely had by way of the air conduits 3, and it will be understood that the oil reservoir will be supported upon any suitable standard 45 arranged to support the oil reservoir along its edges to cause air to pass upwardly through said conduits, this air dividing in opposite paths as it impinges against the V-shaped strips 27' so as to pass over the members 5, 70 part of this air making exit through the ports 28 formed upon the strips 27'. In this way the heater will not smoke and no annoyance will be caused from the use of hydrocarbons as fuel. When the tubular 75 member 41 is in use, air may pass through the ports 27 to promote combustion.

Numerous modifications may be resorted to in practice without departing in principle from the details of construction herein 80 disclosed.

What I desire to secure and claim by Letters Patent is:—

1. In combination an oil reservoir, a plurality of spaced-apart upright wick-containing members projecting above said reservoir and communicating with the interior thereof, air conduits being formed between said members passing through said reservoir and opening out of the bottom 90 thereof, wicks adjustably disposed in said members, a casing resting on said reservoir and surrounding said wick-containing members, means for holding said casing against displacement, longitudinally-extending V-shaped strips carried by said casing disposed in the line of passage of air passing through said conduits, said strips having a series of longitudinally-extending ports, said casing having atmospheric openings. 95

2. In a device of the kind described in combination, a reservoir, a casing mounted thereupon, two air draft conduits passing through said reservoir and open at their opposite ends, four wick-containing members 100 projecting above and into said reservoir, each of said air draft conduits disposed between two of said wick-containing members, said casing having a deflector plate disposed centrally at its top, oppositely and outwardly 105 slanting portions formed upon the margins of said deflector plate and extending over the wick-containing members, two partitions extending longitudinally and upwardly of said casing, between said slanting portions and having upwardly and outwardly extending portions thereupon. 110

3. In combination, an oil reservoir, a casing mounted thereupon, four upright wick-containing members projecting into said casing and oil reservoir, a plurality of air draft conduits opening out of the bottom of said oil reservoir and each extending between a pair of said members, V-shaped perforated strips mounted upon said casing 115 120 125 130

above and in line with said air conduits and above the level of said wick-containing members, an outwardly extending rim surrounding the top of said casing and having ports, inwardly-extending flanges merging with said rim, downwardly inclined portions being formed upon said flanges pointing toward said wick-containing members, and means for deflecting heated air over 10 said perforated strips.

4. A device of the kind described comprising an oil reservoir, a plurality of wick-containing members disposed upright in said reservoir and projecting therefrom, a casing arranged to rest upon said reservoir and surround said members, means for holding said casing against displacement, said casing formed with openings communicating with the space between the innermost wick-containing members, a downwardly and centrally disposed plate being mounted upon said casing, a deflector member mounted upon said plate at its top and having downwardly and outwardly inclined rims, said 20 plate extending between said innermost wick-containing members, and upright partitions surrounding said plate and having upwardly and outwardly inclined portions disposed under said deflector member.

25 5. A wick container comprising a relatively narrow rectangular open ended casing, said casing having a reduced upper end, a wick carrier in said casing, said carrier consisting of a slide formed with right angular flanges, said flanges having reduced serrated portions, a plurality of spaced-apart spring arms mounted upon said slide and arranged to engage a wick, a rod passing through said casing, and toothed wheels 30 on said rod arranged to coact with said serrated portions.

40 6. A wick holder comprising a wick casing, said casing having a flat wall and an irregular wall forming a reduced portion at 45 one end of said casing, a wick carrier slid-

ingly contacting said irregular wall, a plurality of spring arms mounted in said casing and having deflecting portions arranged to force said wick against the flat wall of said casing, and means for reciprocating said wick carrier.

5. In a device of the kind described, in combination an oil reservoir, a casing projecting above said reservoir in spaced-apart relation, wick containers arranged in said 55 casing, said wick containers being arranged in spaced apart pairs, a bracing strip connecting each pair of said wick containers, a slide moving in each wick container, means carried by said slide for grasping a wick, a 60 rack mounted on said slide, a wick raiser rod passing through the ends of each container, a pinion on said rod meshing with said rack, each of said strips being formed with slots, the projecting ends of said rod 65 resting in said slots, and an operating handle formed upon each of said wick raiser rods.

7. A device of the kind described comprising an oil reservoir, a plurality of 70 wick-containing members disposed in said reservoir and projecting therefrom and communicating therewith, means for conducting air from the bottom of the reservoir over said wick-containing members, a removable open ended casing mounted on said reservoir and surrounding said wick-containing members, means carried by said removable casing for deflecting the air toward said wick-containing members, means 75 for holding said casing against displacement, and means carried by said casing for causing a down draft to descend between pairs of said wick-containing members.

In testimony whereof I affix my signature 85 in presence of two witnesses.
